DOOR MOUNTING

Keith K. Kesling, Dayton, Ohio, assignor to General Motors Corporation, Detroit, Mich., a corporation of Delaware

Application January 17, 1958, Serial No. 709,533

7 Claims. (Cl. 312—328)

This invention relates to refrigerators and particularly to the mounting of a door on a compartment therein.

In the refrigerator cabinet art there has recently been provided in a cabinet or on a door thereof a plurality of small compartments which augment the main food storage chamber of the cabinet and are utilized for the storage of blocks or cuts of cheese and the like and dishes containing food stuffs left over from the dinner table and are desirable to be concealed in compartments. These compartments are preferably closed by separate doors necessitating individual hinging thereof. Hinging of such doors is ordinarily carried out by employing hinges consisting of two or more parts and a separate spring associated therewith and with a door to bias the door closed. This prior hinge arrangement is initially expensive and is tedious and timely to install on or in a refrigerator cabinet and adds to the manufacturing cost thereof. I contemplate the hinging of doors to compartments in a refrigerator cabinet or on its door in an improved and less costly manner.

An object of my invention is to provide a unique door biasing arrangement.

Another object of my invention is to pivotally mount a door on a compartment for swinging movement relative thereto by one-piece combined door hinge pin and hinge spring elements which are readily and removably assembled in place the assembly of which biasingly holds the door centered with respect to an access opening in the compartment.

A further object of my invention is to provide a door mounting and biasing arrangement a part of which is effective while the door is closed to maintain it shut and another part of which is torsioned upon opening the door for closing same.

In carrying out the foregoing objects it is a still further and more specific object of my invention to pivotally mount a door on a compartment by one-piece spring elements in such a manner that portions of the elements are tensioned to bias the door closed and when the door is opened other parts of the elements are torsioned in a direction that will not damage their tensioned portions nor impair the capability thereof to maintain the door closed.

Further objects and advantages of the present invention will be apparent from the following description, reference being had to the accompanying drawings, wherein a preferred form of the present invention is clearly shown.

In the drawings:

Figure 1 is a front view of a refrigerator cabinet showing the cabinet door in open position with compartments on its inner face;

Figure 2 is an enlarged fragmentary sectional view taken on the line 2—2 of Figure 1 showing compartments on the refrigerator cabinet door provided with doors hinged according to my invention;

Figure 3 is an enlarged broken fragmentary sectional view taken on the line 3—3 of Figure 2 through a compartment door showing opposite edges thereof pivotally

2

mounted upon walls of a compartment by one-piece combined hinge pin and hinge spring elements of my invention;

Figure 4 is an enlarged side view of one of the combined hinge pin and hinge spring compartment door mounting elements.

Figure 5 is an end view of the element shown in Figure 4; and

Figure 6 is a fragmentary sectional view taken on the line 6—6 of Figure 3 illustrating the position of portions of a combined hinge pin and hinge spring element on a compartment door readied for mounting on a wall of the compartment.

In the drawings of the present application I show in Figure 1 thereof a refrigerator cabinet generally indicated by the reference numeral 10. Cabinet 10 has a metal shell or housing 11 forming the outer walls thereof and in which there is provided, by an inner metal liner 12 with insulating material thereabout, a food storage chamber 14 having a front access opening. An insulated door structure 15, hingedly mounted upon cabinet 10, normally closes the access opening of food chamber 14. An evaporator, mounted in the top portion of chamber 14 behind a concealing door 16, of a closed refrigerating system associated with cabinet 10 is utilized to cool and cause circulation of air in the food chamber for preserving food products stored therein as is conventional in the art. The construction of door 15 is substantially conventional and it comprises an outer metal pan, an inner molded plastic panel 17 with insulating material 18 (see Figure 2) therebetween. Edges of the door pan and panel 17 are secured together by screws or the like and a resilient gasket 19 disposed and locked between their edges is adapted to seal against the front of cabinet 10. Panel 17 is formed to provide a recess 21 in the inner face of door 15 and a plurality of food supporting shelves extends across the recess. One side of the upper portion of door panel 17 is so shaped and provided with shelves 22 as to form opposed walls of a plurality of compartments 23 within recess 21 in the inner face of door 15 (see Figure 2). Compartments 23 augment the storage capacity of chamber 14 and are utilized to store small blocks or cuts of cheese or the like and left over food products from a dinner table. The shelves 22 are each provided with a raised front lip or rail 24 which prevents articles placed in compartments 23 from slipping off the shelves or striking doors adjacent thereto employed to close the access opening of the compartments upon opening and/or closing swinging movements of the main cabinet door 15. It is to be noted that the bottom wall of compartments 23 or shelves 22 terminate inwardly of the compartment access openings and are substantially flush with a shouldered front door jamb portion 26 of walls 27 of the compartments and which door jamb is provided with opposed flat side surfaces 28.

In accordance with my invention I provide means for pivotally mounting a molded plastic closure member or door 31, having a hand grip or knob 32 (see Figure 1) thereon, at the access opening of each of the compartments 23 for concealing the interior thereof and for movement relative thereto. Since the doors 31 are rather small and of light weight their mounting means may also be of light weight construction. Thus I prefer mounting means for door 31 which comprise a set of one-piece combined door supporting hinge pin and hinge spring elements. In Figures 4 and 5 of the drawings I show one of such elements formed of round spring wire bent and coiled in a particular manner as will be presently described. Since the plurality of compartment doors 31 are to be mounted at opposite edges thereof upon opposed sides or walls of compartments 23 two differently bent and coiled spring elements to

form right and left mounting means are employed. These elements are formed from round music wire of approximately .041 inch in diameter and consequently are herein illustrated on an enlarged scale. The spring wire element, generally represented by the reference numeral 34, disclosed in Figure 4 forms a mounting means for the right hand edge of a door 31, as viewed in Figures 1 and 3 of the drawings, and a similar but oppositely bent and coiled wire element generally represented by the reference numeral 35 (see Figure 3) forms a mounting means for the left hand edge of a door 31. The element 34 comprises a predetermined cut length of spring wire which has an elongated part 36 intermediate its ends bent over as at 37 and extending along another elongated part 38 thereof. Elongated parts 36 and 38 of spring element 34 are wrapped or coiled around one another in one direction and they form the hinge pin portion of this one-piece element. A portion projecting outwardly from coiled part 36 of wire element 34 is bent as at 39 to provide a resilient projection 40 extending laterally relative thereto and which projection is further bent at 41, 42 and 43 to provide a hook-like end 44 thereon. A portion projecting from coiled part 38 of wire element 34 is bent at 46 and 47 to provide an end 48 thereon. The other or left hand spring element 35 is bent similar to element 34 but has its hinge pin forming portion coiled in an opposite direction to that of element 34. After so coiling and shaping the spring elements 34 and 35 they assume a normal or free position as shown in Figures 5 and 6 respectively of the drawings wherein the projecting ends thereof are angularly or arcuately spaced from one another about the axis of their elongated coiled parts 36 and 38. In this free position of the elements 34 and 35 any force applied to the projecting ends thereof in a direction to move the ends 44 and 48 toward one another as viewed in Figures 5 and 6 tends to more tightly coil the elongated parts 36 and 38 which thereby tensions the projecting portions of the elements. The elements 34 and 35 are in this manner rendered capable of providing a biasing effect or action in a circular direction about the parts 36 and 38 thereof when their ends 44 and 48 are brought into the same plane with one another. The laterally extending portion 40 of elements 34 and 35 is resilient and is springable to produce a biasing action in a direction paralleling the extension of elongated parts 36 and 38 thereof.

The doors 31 are adapted to be removably mounted upon opposed side walls of the compartments 23 for closing the access opening thereof and for vertical swinging movement relative thereto to open the compartments. Thus I assemble one of each of the one-piece combined hinge pin and hinge spring elements 34 and 35 to opposite side edges of a door 31 and hold the door substantially in the position thereof shown in Figure 6 of the drawings. This assembly consists in inserting the elongated hinge pin parts 36 and 38 of the right and left hand elements 34 and 35 into bores 51 and 52 respectively (see Figure 3) provided in the lower opposed side edge portions of a door 31. At the time of this insertion the end 48 of the opposed elements 34 and 35 is also inserted into smaller bores 53 and 54 provided in the side edges of door 31 above and in vertical alignment with the bores 51 and 52. In this manner the end 48 of each element 34 and 35 is anchored to a door 31 for swinging movement therewith and have portions thereof concealed within the door. The end 44 of opposed elements 34 and 35 assembled upon a door 31 can be forced or sprung toward and past the inner surface of the door, as viewed in Figure 6 of the drawings, and then the projection 40 on these elements are compressed in a direction toward one another at the inner side of the door. This permits door 31 to be moved, from the position thereof shown in Figure 6, into the compartment access open-

ing bounded by opposite side surfaces 28 of the shoddered door jamb thereof. Portions 40 and 44 of each opposed element 34 and 35 are now brought into alignment with the cavities 56 and 57 provided in door jamb surfaces 28 whereupon the compressive force applied to projections 40, toward one another, is released and the projections 40 snap into the opposed cavities 57 with the hook end 44 of the elements snapping into cavities 56. Hands of the assembler are removed from door 31 and the door is thereby pivotally mounted in position within the door jamb at the front of a compartment 23. The ends 44 of elements 34 and 35 are inset within or anchored in the cavities 56 while the resilient part 40 thereof, intermediate bends 41 and 39, are inset within or anchored in the cavities 57 so as not to interfere with swinging movement of a door 31 and to substantially conceal these parts of the elements at least while the door is closed. This springing and releasing of elements 34 and 35 in addition to tensioning same in a circular direction, about the parts 36 and 38 thereof, whereby they normally bias a door 31 closed also maintains the resilient projecting parts 40 thereof slightly compressed between opposed side walls of a compartment 23 whereby the portions 40 bias and at all times hold the door centered with respect to the compartment access opening. A door 31 mounted as described and as shown is normally biased shut within the door jamb and with its edge portions bearing against the shoulder or flange 26 thereof. A door 31 is vertically swingable about its pivotal mounting, hinge pin portions or parts 36 and 38 of the spring elements 34 and 35, to open a compartment access opening. Thus when the knob 32 of a door 31 is grasped by the hand and pulled forwardly and downwardly the door closing biasing action of spring elements 34 and 35 is manually overcome and the door is swung open (see Figure 2). The downward opening swinging movement of a door 31 causes twisting of the coiled elongated hinge pin parts 36 and 38 of spring elements 34 and 35 in a direction opposite the direction of coil thereof which tends to unwind their parts 36 and 38 and torsions at least one of the coiled parts for a purpose to be presently described. Upon releasing an opened door 31 it swings or is returned to closing position, automatically in response to or under the influence of the tensioned parts and the torsioned coiled part of the hinge pin portion of elements 34 and 35, for again rendering the elements effective to fully close the door and maintain it shut. I have discovered that by torsioning an elongated coiled hinge pin portion of one-piece combined wire elements of the character disclosed in a direction opposite their coiled direction instead of in the direction of coil thereof they are not tightly twisted upon opening movements of a door thus I retain their efficient biasing effect over long periods of time and reduce breakage or fracture thereof to a minimum. This is particularly important in the use of one-piece wire spring elements of the size and type disclosed. Should a door 31 become damaged or broken necessitating replacement thereof a sharp pointed tool such as a screw driver or the like may be wedged into a cavity 57 behind a portion of the resilient part 40 of an element 34 or 35 therein to spring same outwardly of the cavity and permit detachment of a door from walls of a compartment.

From the foregoing it should be apparent that my one-piece combined hinge pin and hinge spring elements together with the novel mounting thereof eliminate the necessity of hingedly mounting a door by two or three part hinges and screws for securing the parts of the hinges. By mounting the hinging elements of my door biasing devices in the manner disclosed the elements are substantially concealed from view, at least while the doors are biased shut, and thus the elements do not detract from the smooth neat appearance of the front 75 of the compartments. The torsioning of the hinge pin

portion of the door hinging spring elements in a direction opposite the coiled direction thereof does not unduly stretch, twist or strain the metal of the elements and they thereby retain a predetermined resiliency to insure of their constant biasing of a door. My combined door supporting hinge pin and hinge spring elements are economical to produce, readily assembled and after being assembled bias a door shut and when a door is moved about its pivotal mounting this biasing action is augmented or increased by torsioning the elements in a direction to unwind the parts 36 and 38 rather than to wind them tighter but in so doing energy is stored therein for returning the door to the closed position when one releases the door. In this manner a door is easily opened and more readily held in an open position while access to a compartment is being had and this feature is particularly desirable in the use or operation of light weight doors normally closing small auxiliary compartments in a refrigerator cabinet or on the door thereof.

While the form of embodiment of the invention as herein disclosed constitutes a preferred form, it is to be understood that other forms might be adopted, as may come within the scope of the claims which follow.

What is claimed is as follows:

1. In combination, walls defining a compartment provided with an access opening and a door for the opening, means pivotally mounting opposite edges of said door upon opposed sides of said compartment for movement relative thereto, each of said means comprising a one-piece spring element, said elements each including an elongated part bent over and extending along another elongated part thereof, said parts of said elements being disposed substantially in alignment with the axis of movement of said door and having ends projecting therefrom, the end of one elongated part of each of said elements being anchored to said door for movement therewith and the end of the other elongated part of said elements being bent to extend laterally therefrom, said laterally extending end of said other elongated part of said elements being anchored upon the opposed sides of said compartment, said anchoring of the ends of said one-piece spring elements tensioning same to normally bias said door closed, said door being swingable about said elongated parts of said elements to open and close the access opening of said compartment, and the laterally extending end of said other elongated part of said elements being resilient and bearing against said opposed sides of the compartment to hold said door centered with respect to the opening therein.

2. The combination defined by claim 1 wherein the resilient end of the other elongated part of the spring elements are movable away from sides of the compartment to detach the door therefrom.

3. The combination defined by claim 1 wherein one of the elongated parts of the spring elements is coiled around another elongated part thereof and is torsioned in a direction opposite the door biasing direction of the elements by swinging the door open.

4. In combination, walls defining a compartment provided with an access opening and a door for the opening, means pivotally mounting opposite edges of said door upon opposed walls of said compartment inwardly of the opening therein for movement relative thereto, each of said means comprising a one-piece combined door

supporting hinge pin and hinge spring element, said elements each including an elongated part bent over and extending along another elongated part thereof to form the hinge pin portion of the elements, said elongated parts of each element being disposed in an aperture provided in said opposite edges of the door and having ends projecting therefrom, the end of one elongated part of each of said elements being anchored to said door for movement therewith and the end of the other elongated part of said elements being bent to extend laterally therefrom, said laterally extending end of said other elongated part of said elements being anchored in a cavity provided in the opposed walls of said compartment, said anchoring of the ends of said one-piece elements tensioning same to normally bias said door closed, said door being swingable about the hinge pin portion of said elements to open and close the access opening of said compartment, and the laterally extending end of said other elongated part of said elements being resilient and bearing against said opposed compartment walls to hold said door centered within said compartment access opening.

5. The combination defined by claim 4 wherein the resilient end of the other elongated part of the elements are snapped into the cavity in the compartment walls and are springable outwardly thereof to detach the door from the compartment.

6. The combination defined by claim 4 wherein one of the elongated parts of the one-piece elements is coiled around another elongated part thereof and is torsioned in a direction opposite the door biasing direction of the elements by swinging the door open.

7. In combination, walls defining a compartment provided with an access opening and a door for the opening, means pivotally mounting opposite edges of said door upon opposed walls of said compartment for movement relative thereto, at least the means at one edge of said door comprising a one-piece combined door supporting hinge pin and hinge spring element, said element including an elongated part bent over and extending along another elongated part thereof to form the hinge pin portion of the element, said parts of said element being disposed substantially in alignment with the axis of movement of said door and having ends spaced therefrom and directed in opposite directions, the end on one elongated part of said element being anchored to said door for movement therewith and the end on the other elongated part of said element being stationarily anchored to a wall of said compartment, said anchoring of the ends of said one-piece spring element tensioning same to normally bias said door closed, said door being swingable about said elongated parts of said element to open and close the access opening of said compartment, and that portion of said spring element between said end thereof anchored to said compartment and the other elongated part of the element being resilient and bearing against said compartment wall to hold said door centered within the compartment access opening.
